[57] CLAIM

The ornamental design for a pinball game cabinet, substantially as shown and described.

DESCRIPTION

FIG. 1 is a perspective view of a pinball game cabinet embodying my new design;

FIG. 2 is a top plan view of the cabinet shown in FIG. 1;

FIG. 3 is a side elevational view of the cabinet shown in FIG. 1;

FIG. 4 is a front elevational view of the cabinet shown in FIG. 1; and

FIG. 5 is a back elevational view of the cabinet shown in FIG. 1.

The broken line showing of supports in the drawing is for illustrative purposes only.
